US0D1109192S

(12) **United States Design Patent** (10) **Patent No.:** **US D1,109,192 S**
(45) **Date of Patent:** **** Jan. 13, 2026**

(54) **TRACTOR**

(71) Applicant: **CLAAS KGaA mbH**, Harsewinkel (DE)

(72) Inventors: **Markus Matthies**, Bielefeld (DE); **Karim Jedlitschka**, Halle (DE); **Maximilian Bohl**, Warendorf (DE)

(73) Assignee: **CLAAS KGaA mbH**, Harsewinkel (DE)

(**) Term: **15 Years**

(21) Appl. No.: **29/886,954**

(22) Filed: **Mar. 15, 2023**

(30) **Foreign Application Priority Data**

Sep. 16, 2022 (EM) 009176282

(51) **LOC (15) Cl.** **15-03**

(52) **U.S. Cl.**

USPC **D15/31**
